UNITED STATES PATENT OFFICE.

CHARLES T. BOYER, OF INDIANAPOLIS, INDIANA.

COLLAR-BUTTON.

1,368,423.

Specification of Letters Patent. Patented Feb. 15, 1921.

Application filed April 14, 1920. Serial No. 373,806.

To all whom it may concern:

Be it known that I, CHARLES T. BOYER, a citizen of the United States, residing at Indianapolis, in the county of Marion and State of Indiana, have invented a new and useful Collar-Button, of which the following is a specification, reference being had to the accompanying drawings and to the letters and figures of reference marked thereon.

This invention relates to a device that is designed for connecting a collar to the rear or back portion of a shirt, and the invention has reference more particularly to the type of collar button that is designed so as to be unobtrusive and adapted to either hold a neck-tie or to permit a neck-tie differently arranged to freely slide thereon.

An object of the invention is to provide an improved collar button which shall be so constructed as to be adapted to be used in either horizontal button-holes or in vertical button-holes and which shall be adapted to be used with comfort to the wearer. Another object is to provide an improved collar button which shall be adapted to hold neckties when worn on a standing collar from slipping up to the top of the collar, and which shall be adapted also to permit a neck-tie to freely slide thereon when worn with a turned-down collar. A further object is to provide a collar button of improved construction which may be strongly formed of a single piece of sheet metal and which shall be thin so as to not cause the wearer pain nor be difficult to connect with garments, and which shall be simple and inexpensive yet be durable and economical in use.

With the above-mentioned and other objects in view, the invention consists in an improved collar button having certain novel and useful features, and in the structural improvements as hereinafter particularly described and further defined in the accompanying claims.

Referring to the drawings,—Figure 1 is a perspective view illustrating the manner of using the improved collar button in connection with a turned-down collar; Fig. 2 is a perspective view showing the neck band of a shirt having the collar button connected thereto whereby to fasten a collar to the neck band; Fig. 3 is a perspective view of

the improved collar button constructed substantially in accordance with the invention; Fig. 4 is a vertical section of a shirt neck band of familiar construction having the collar button connected therewith; Fig. 5 is a fragmentary perspective view illustrating a standing collar on a neck band and the improved collar button connected therewith and holding a neck-tie in the desired position; Fig. 6 is a fragmentary elevation of a turned-down collar with a neck band and the improved collar button connected therewith, and a neck-tie in association therewith, portions being broken away to disclose other portions; and, Fig. 7 is a section approximately on the line VII—VII in Fig. 3.

Similar reference characters in the different figures of the drawings indicate corresponding elements or features of construction herein referred to in detail.

In the drawings the upper portion of a garment 1, more particularly a shirt is illustrated in outline, and the garment has a neck band 2 usually composed of several thicknesses of material and having an outer portion 3 that is not connected at its lower edge to the main portion of the neck band, to permit a rear collar button to be inserted into the space behind the outer portion 3 which has a slot or button-hole 4 therein usually arranged horizontally so as to extend longitudinally in the neck band. In some cases a turned-down collar is used which comprises a main portion 5 and a turned over outer portion 6, the main portion having a rear button-hole or slot 7 which is approximately vertical, being transverse relatively to the collar. In other cases a standing collar 8 is used which has a rear button-hole or slot 9 therein which usually is horizontal, so as to extend longitudinally in the collar.

The collar button comprises a base portion or anchor plate 10, and shank and head portion, all formed of a single piece of metal. The base portion 10 is longer in one direction than transversely and a shank 11 extends from the middle portion of the lower edge thereof approximately at right angles to the face of the base portion. An improved button member comprises a body portion 12 that extends from the shank 11 at approximately right angles thereto, a

neck 13 that is relatively narrower than the portion 12 and extends from the terminal of said portion, and a head portion 14 that extends from the neck and is relatively 5 broader than the neck, being approximately as broad as the body portion 12. The head has a convex front or outer face 15 that extends as at 16 to the neck 13, and preferably the head portion has a concave back or inner side 17. Preferably the base or anchor plate 10 has projecting fingers 18 and 19 thereon to prevent it from being turned over accidentally when connecting a collar to the button or when in use.

15 In practical use when the turned-down collar is required, if the main portion 5 thereof has a vertical button-hole 7 the head 14 is forced through the button-hole until the neck 13 is fairly in the button-hole 20 which is permitted to partially close on the neck without causing the fabric about the button-hole to be distorted or puckered. The neck-tie band 20 which is arranged between the two portions of the collar may be 25 longitudinally adjusted without it being caught and held on the improved button, the head 14 being the only portion presented to the tie band, and the outer convex face 15 being against the tie band permits the latter 30 to slide freely thereon. In case a standing collar is required and if it has a horizontal button-hole 9 the latter receives the shank 11, and the tie band 21 may be readily placed under the body portion 12 and the 35 remainder of the button member and may be readily shifted to the desired position.

Having thus described the invention, what is claimed as new is—

1. A collar button comprising an anchor plate, a shank on the anchor plate, and a 40 button member consisting of a flat body portion extending from the shank, a neck portion that is relatively narrower than the body portion extending from the body portion, and a head portion that is relatively 45 broader than the neck portion extending from the neck portion, said head portion having a convex front face and a concave rear face which extends to said neck portion.

2. A collar button comprising an oblong 50 anchor plate, two fingers on one of the longer edges of the anchor plate adjacent to opposite ends respectively thereof, a shank on said edge between said fingers and extending from said edge at an angle to the face 55 of said plate, a flat body portion extending from the end of said shank and approximately parallel to the plane of the front of said plate, a neck portion that is relatively narrower than said body portion extending 60 from said portion, and a head portion that is relatively broader than the neck portion extending from the neck portion, said head portion having two edges that are divergent from the neck portion. 65

In testimony whereof, I affix my signature in presence of two witnesses.

CHARLES T. BOYER.
